UNITED STATES PATENT OFFICE

124,298

DESIGN FOR A PULL SWITCH

Onnie Mankki, Cleveland, Ohio, assignor to Electric Service Supplies Company, Philadelphia, Pa., a corporation of Pennsylvania

Application October 14, 1939, Serial No. 87,662

Term of patent 14 years

To all whom it may concern:

Be it known that I, Onnie Mankki, a citizen of the United States and a resident of Cleveland, county of Cuyahoga, State of Ohio, have invented a new, original, and ornamental Design for Pull Switch, of which the following is a specification, reference being had to the accompanying drawing, forming a part thereof, wherein:

Figure 1 is a perspective view of a pull switch showing my design;

Figures 2 and 3 are side and end elevational views thereof; and

Figure 4 is a top plan view thereof.

The pull switch includes as a bottom part thereof a flat base plate or member which cooperates with the other part shown in the drawing to provide an enclosed housing for the internal switch elements (not shown).

I claim:

The ornamental design for a pull switch, substantially as shown and described.

ONNIE MANKKI.
